US00D898094S

(12) **United States Design Patent** (10) Patent No.: **US D898,094 S**
(45) Date of Patent: ** Oct. 6, 2020

(54) **LOUPE**

(71) Applicant: **Carson Optical, Inc.**, Ronkonkoma, NY (US)

(72) Inventors: **Peter Hyunjoon Kwon**, Alpine, NJ (US); **Isabelle Cochran**, Austin, TX (US)

(73) Assignee: **Carson Optical, Inc.**, Ronkonkoma, NY (US)

(**) Term: **15 Years**

(21) Appl. No.: **29/659,606**

(22) Filed: **Aug. 10, 2018**

(51) LOC (12) Cl. **16-06**

(52) U.S. Cl.

USPC **D16/135**

(58) **Field of Classification Search**

USPC D16/130, 134, 135, 136; D10/62, 71
CPC G01B 3/04

See application file for complete search history.

(57) **CLAIM**

The ornamental design for a loupe, as shown and described.

DESCRIPTION

FIG. 1 is a perspective view of a loupe showing our new design;

FIG. 2 is a back elevational view thereof;

FIG. 3 is a front side elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dotted lines are intended to show features that are environmental only and form no part of the claimed design.
